REFRIGERATION APPARATUS

Graham S. McCloy, East Longmeadow, Mass., assignor to Westinghouse Electric & Manufacturing Company, East Pittsburgh, Pa., a corporation of Pennsylvania

Application January 29, 1938, Serial No. 187,591

18 Claims. (Cl. 62—115)

This application is a continuation in part of my application, Serial No. 122,905, filed January 29, 1937 for Refrigeration apparatus.

It is an object of my invention to provide refrigeration apparatus in which the efficiency is improved by the use of novel heat exchange devices in the system.

It is another object of my invention to provide a novel arrangement of parts for controlling the flow of refrigerant between the high and the low pressure sides of a refrigerating system.

It is a further object of my invention to provide an improved heat exchanger between the suction conduit and capillary tube of a refrigerating system, in which the conduit and tube are metallically connected together for a considerable portion of their respective lengths.

It is still another object of my invention to provide a novel heat exchanger for a refrigerating system and to improve the operation of the heat exchanger by surrounding it with heat insulation, preferably heat insulation associated with the refrigerator cabinet.

It is still a further object of my invention to provide a heat exchanger embedded in the cabinet heat insulation which is readily applied to and removed from the refrigerator cabinet with other portions of the refrigerating system.

It is another object of my invention to provide a novel heat exchanger between the capillary tube and suction conduit of a refrigerating system which is associated with a heat insulated cabinet wherein part of the heat exchanger is disposed exteriorly of the cabinet and another part of the heat exchanger is disposed in the heat insulation.

It is yet another object of my invention to provide an extremely compact heat exchanger by the novel arrangement of the capillary tube with respect to the suction conduit.

These and other objects are effected by my invention as will be apparent from the following description and claims, taken in connection with the accompanying drawings, forming a part of this application, in which:

Fig. 1 is a diagrammatic view of a refrigerating system embodying my invention;

Fig. 2 is a vertical sectional view of a portion of a refrigerator cabinet illustrating the application of my improved refrigerating system to a refrigerator cabinet;

Fig. 3 is an elevational view of the back of the refrigerator cabinet and illustrates the heat exchanger disposed exteriorly thereof; and,

Fig. 4 is an enlarged cross-sectional view, taken

on line IV—IV of Fig. 3 of the heat exchanger which is disposed exteriorly of the cabinet.

Referring specifically to the drawings for a detailed description of my invention, numeral 11 designates a compressor for compressing refrigerant vapor and numeral 12 designates a motor for driving the compressor. Compressed refrigerant vapor is conveyed through a discharge conduit 13 to a condenser 14, wherein it is cooled by a fan 15 and thus liquefied. Condensed refrigerant is then conveyed to portions 20 and 21 of a tube of considerable length and relatively small diameter, sometimes referred to as a capillary tube. After passing through the portions 20 and 21 of the capillary tube, the refrigerant enters 16 a portion 22 of the capillary tube, which is preferably helically coiled as shown in Figs. 1 and 2 for a substantial portion of its length.

Refrigerant then enters an evaporator or expansion vessel 24, herein shown as a sheet metal, flooded type, wherein the refrigerant expands and absorbs heat. Vaporized refrigerant is withdrawn from the evaporator 24 by the compressor 11 through a conduit 25. The gas passing through the conduit 25 is relatively cool, and is, therefore 26 disposed in heat exchange relation as shown diagrammatically in Fig. 1, with the portions 20 and 21 of the capillary tube, which contains relatively 28 warm liquid refrigerant from the condenser 14.

The compressor driving motor 12 is stopped and 30 started by means of a temperature controlled switch 26 which has the contacts 29 closed and opened in response to the temperature of the evaporator through the expansion and contraction of the fluid in a bulb 27 and bellows 28. 35 When the contacts 29 are bridged, the motor is energized from the line L₁ and L₂ and when the bellows 28 contracts due to a lower temperature of the evaporator 24, the contacts 29 are opened, deenergizing the motor.

Referring now specifically to Figs. 2 and 3 of the drawings, a refrigerator cabinet 31, having heat insulation 30, is shown. An aperture 32 is provided in one of the heat insulated walls of the cabinet 31 for the reception of the evaporator 24, 45 which is disposed normally in a food storage compartment 34 formed in the cabinet 31. The evaporator 24 is preferably supported from a closure 35 for the aperture 32 by bracket 36. The closure 35 is filled with heat insulation 37. As 50 shown in Fig. 3, the refrigerating mechanism comprising the motor, compressor and preferably the condenser are disposed in a machinery compartment 40 positioned below the food storage compartment 34.

As best shown in Figs. 2 and 3, the suction conduit 25 and the portion 20 of the capillary tube extend from the machinery compartment 40 up the back of the cabinet exteriorly thereof, to the point where they enter the heat insulated closure 35. The suction conduit 25 and portion 20 of the capillary tube are disposed in metallic heat exchange relation, preferably by soldering the two together, for substantially their entire extent after leaving the machinery compartment 40 until they enter heat insulated closure 35. The suction conduit 25 is thus bonded to the capillary tube. This arrangement provides a portion of my heat exchanger and may be utilized without any further heat exchanger with resulting increase in efficiency of the refrigeration system, because the liquid in the capillary tube is not only cooled, but is prevented from expanding, with resulting loss of useful refrigeration. Furthermore, the suction tube, particularly, has a tendency to condense moisture thereon, which may drip on the floor, and by disposing the capillary tube containing warm liquid refrigerant in heat exchange relation with the portion of the suction conduit which extends exteriorly of the cabinet, sweating and dripping are substantially eliminated.

A second heat exchanger is also provided, which may be used separately from or in conjunction with the heat exchanger just described. As shown in Figs. 2 and 3, the second heat exchanger is formed by coiling a portion 38 of the suction conduit 35 and imbedding it in the heat insulation 37 of the closure 35. The portion 21 of the capillary tube is helically wound about the portion 38 of the suction conduit 25 and is preferably soldered thereto. The coiled portion 22 of the capillary tube is also embedded in the heat insulation 37.

By retarding the expansion of refrigerant until it reaches the evaporator 24, and by cooling the liquid refrigerant in the portion 21 of the capillary tube, the efficiency of the system is increased because a greater portion of the refrigerant compressed and condensed performs useful cooling by vaporization in the evaporator. In addition, the liquid refrigerant is cooled so that sensible heat need not be abstracted therefrom by vaporization of liquid in the evaporator 24, thus increasing the efficiency of the evaporator. Since the heat exchanger 20 and the helical coil 22 of the capillary tube are embedded in the insulation 37, the liquid in the capillary tube is not heated by contact with the relatively warm ambient air and expansion of the liquid is also retarded in this manner.

When the two heat exchangers are used in conjunction, as shown in the drawings, a very efficient heat exchanger is obtained since the coolest vaporized refrigerant is in heat exchange relation with the coolest liquid refrigerant and the warmest with the warmest. A substantial temperature differential is, therefore, maintained between the gas and the liquid at all points where the capillary tube and suction conduit are in heat exchange relation. Furthermore, a very important reason for the increase in efficiency of the heat exchangers, whether used separately or conjointly, is because of the large length of capillary tube and suction conduit which are metallically connected together. Any slight increase in work which must be done by the compressor due to superheating of the suction gas is more than offset by the gain effected.

From the foregoing it will be apparent that I

have provided an improved refrigerating system from the standpoint of efficiency and have devised a novel flow control device between the high and low sides of the system, which device materially increases the efficiency of the machine. 5

While I have shown my invention in but one form, it will be obvious to those skilled in the art that it is not so limited, but is susceptible of various other changes and modifications without departing from the spirit thereof, and I desire, therefore, that only such limitations shall be placed thereupon as are imposed by the prior art or as are specifically set forth in the appended claims. 10

What I claim is: 15

1. In refrigerating apparatus, the combination of a compressor, a condenser, an evaporator, a refrigerator cabinet embodying a cooling compartment having an aperture therein for reception of the evaporator, a heat insulating closure 20 for the aperture, a tube of small diameter and considerable length for restricting the flow of refrigerant from the condenser to the evaporator, and a suction conduit connecting the evaporator and the compressor, said tube and said suction 25 conduit being disposed in heat exchange relation for a substantial portion of their lengths, said heat exchange portions being embedded in said heat insulated closure.

2. In refrigerating apparatus, the combination 30 of a compressor, a condenser, an evaporator, a refrigerator cabinet embodying a cooling compartment in which said evaporator is disposed, heat insulation surrounding said cooling compartment, a tube of small diameter and considerable length for restricting the flow of refrigerant from the condenser to the evaporator, and a suction conduit for conveying vaporized refrigerant from the evaporator, said tube and said suction conduit being disposed in heat exchange 35 relation for substantial portions of their lengths, said portions being surrounded by heat insulation, and another portion of said tube between the heat exchanger and the evaporator and embedded in said last-named heat insulation. 45

3. In refrigeration apparatus, the combination of a cabinet embodying a storage compartment and a machinery compartment, an evaporator associated with the storage compartment for abstracting heat therefrom, a refrigerating mechanism disposed in the machinery compartment, a capillary tube for conveying liquefied refrigerant from said mechanism to said evaporator and a suction conduit for conveying vaporized refrigerant from said evaporator to said mechanism, 50 both said suction conduit and said capillary tube extending for a considerable distance outside said cabinet and being bonded in intimate metallic heat exchange relation with each other for a substantial portion of said distance. 60

4. In refrigeration apparatus, the combination of a cabinet embodying a storage compartment, an evaporator associated with the storage compartment for abstracting heat therefrom, a refrigerating mechanism associated with the cabinet, a capillary tube for conveying liquefied refrigerant from said mechanism to said evaporator and a suction conduit for conveying vaporized refrigerant from said evaporator to said mechanism, 65 said suction conduit and capillary tube being metallically bonded to each other in intimate heat exchange relationship for a considerable portion of their respective lengths and exposed to the ambient atmosphere. 70

5. In refrigeration apparatus, the combination 75

- of a cabinet embodying a storage compartment and a machinery compartment disposed therebelow, an evaporator for abstracting heat from the storage compartment disposed adjacent the 5 top of the storage compartment, a refrigerating mechanism disposed in the machinery compartment, said mechanism including a condenser in which refrigerant is condensed, a capillary tube and a suction conduit for conveying liquid and 10 gaseous refrigerant, respectively, between the evaporator and the mechanism, said cabinet having an opening therein adjacent the evaporator through which said tube and conduit extend, said capillary tube and suction conduit being metallically 15 bonded together in intimate heat exchange relationship from approximately the point where they leave the machinery compartment near the bottom of the cabinet to the point where they enter the cabinet adjacent the evaporator.
- 20 6. In refrigeration apparatus, the combination of a cabinet embodying a storage compartment and a machinery compartment disposed therebelow, an evaporator for abstracting heat from the storage compartment disposed adjacent the 25 top of the storage compartment, a refrigerating mechanism disposed in the machinery compartment, said mechanism including a condenser in which refrigerant is condensed, a capillary tube and a suction conduit for conveying liquid and 30 gaseous refrigerant, respectively, between the evaporator and the mechanism, said cabinet having an opening in its back adjacent the evaporator through which said tube and conduit extend, said capillary tube and suction conduit being metallically 35 bonded together in intimate heat exchange relationship exteriorly of the back of the cabinet from the point where they leave the machinery compartment near the bottom of the cabinet to the point where they enter the 40 cabinet.
- 45 7. In refrigeration apparatus, the combination of a cabinet embodying a storage compartment and a machinery compartment, an evaporator associated with the storage compartment for abstracting heat therefrom, a refrigerating mechanism disposed in the machinery compartment, a capillary tube for conveying liquefied refrigerant from said mechanism to said evaporator and a suction conduit for conveying vaporized refrigerant from said evaporator to said mechanism, both said suction conduit and said capillary tube extending for a considerable distance outside said cabinet and being bonded in 50 intimate metallic heat exchange relation with each other for a substantial portion of said distance.
- 55 8. In refrigeration apparatus, the combination of a heat insulated cabinet embodying a storage compartment, an evaporator disposed in the storage compartment for abstracting heat therefrom, a refrigerating mechanism associated with the cabinet, a capillary tube for conveying liquefied refrigerant from said mechanism to said evaporator and a suction conduit for conveying vaporized refrigerant from said evaporator to said mechanism, said suction conduit and capillary tube being metallically connected to each other for a considerable portion of their respective lengths, and a portion of said conduit and 60 said capillary tube being embedded in the heat insulation of the cabinet adjacent the outlet end of the capillary tube, said latter portions being in heat exchange relation with each other.
- 65 9. In refrigeration apparatus, the combination of a cabinet embodying a storage compartment 65
- surrounded by heat insulation and a machinery compartment disposed therebelow, an evaporator for abstracting heat from the storage compartment disposed adjacent the top of the storage compartment, a refrigerating mechanism disposed in the machinery compartment, said mechanism including a condenser in which refrigerant is condensed, a capillary tube and a suction conduit for conveying liquid and gaseous refrigerant, respectively, between the evaporator and the mechanism, said cabinet having an opening therein adjacent the evaporator through which said tube and conduit extend, said capillary tube and suction conduit being metallically 10 connected together from substantially the point where they leave the machinery compartment near the bottom of the cabinet to the point where they enter the cabinet, and a portion of said suction conduit and said capillary tube being embedded in the heat insulation of the cabinet adjacent the outlet end of the capillary tube, said latter portions being in heat exchange relation with each other.
- 15 10. In refrigeration apparatus, the combination of a cabinet embodying a storage compartment and a machinery compartment disposed therebelow, an evaporator for abstracting heat from the storage compartment disposed adjacent the top of the storage compartment, a refrigerating mechanism disposed in the machinery compartment, said mechanism including a condenser in which refrigerant is condensed, and a capillary tube and a suction conduit for conveying liquid and gaseous refrigerant, respectively, between the evaporator and the mechanism, said cabinet having an opening in its back adjacent the evaporator through which said tube and conduit extend, said capillary tube and suction conduit being metallically 20 connected together exteriorly of the back of the cabinet from the point where they leave the machinery compartment near the bottom of the cabinet to the point where they enter the cabinet, and a portion of said suction conduit and said capillary tube being embedded in the heat insulation of the cabinet adjacent the outlet end of the capillary tube, said latter portions being in heat exchange relation with each other.
- 25 11. In refrigeration apparatus, the combination of a heat insulated cabinet embodying a storage compartment and a machinery compartment, an evaporator disposed in the storage compartment for abstracting heat therefrom, said storage compartment having an opening therein through which said evaporator is insertable, a heat insulated plug for closing said opening, a refrigerating mechanism disposed in the machinery compartment, a capillary tube for conveying liquefied refrigerant from said mechanism to said evaporator and a suction conduit for conveying vaporized refrigerant from said evaporator to said mechanism, both said suction conduit and said capillary tube extending for a considerable distance outside said cabinet and being in metallic 30 heat exchange relation with each other for a substantial portion of said distance, and a portion of said suction conduit and said capillary tube being embedded in said heat insulated plug, said latter portions of the capillary tube and the suction conduit also being in heat exchange relation 35 with each other.
- 35 12. In a refrigerating system, an expansion vessel, a tube for conducting the refrigerant liquid to the expansion vessel, said tube being of small diameter to restrict the flow of the re- 40
- 45 45
- 50 50
- 55 55
- 60 60
- 65 65
- 70 70
- 75 75

- frigerant liquid therethrough, and a conduit of substantially larger diameter than said tube for conducting the refrigerant vapor from said expansion vessel, substantial portions of the walls 5 of said tube and conduit being bonded together by a high heat transmitting material into intimate heat exchange relationship with one another and exposed to the ambient atmosphere.
13. In a refrigerating system, in combination, 10 a compressor, a condenser, an evaporator, a tube of small diameter and considerable length for restricting the flow of refrigerant liquid from the condenser to the evaporator, and a suction conduit of substantially larger diameter than said tube for conveying vaporized refrigerant from the evaporator, substantial portions of the walls of said tube and said suction conduit being disposed in intimate metallic heat conducting relationship and exposed to the ambient atmosphere.
14. In refrigerating apparatus, the combination 15 of a heat insulated cabinet, an evaporator for abstracting heat from said cabinet, refrigerant-supplying apparatus outside of said cabinet, a capillary flow-restricting tube for conducting the relatively warm liquid refrigerant from said refrigerant supplying apparatus to said evaporator and providing a pressure differential therebetween, and a suction tube for conducting the relatively cold vaporized refrigerant from the evaporator to the refrigerant-supplying apparatus, said capillary and suction tubes being in intimate heat conducting relationship with one another in the ambient atmosphere adjacent said cabinet, whereby the temperature of the 20 suction tube in the ambient atmosphere is raised above the dew-point temperature thereof by the relatively warm liquid refrigerant in the capillary tube regardless of the temperature of the vaporized refrigerant in the suction tube.
15. In refrigeration apparatus, the combination 25 of a heat insulated cabinet, an evaporator for abstracting heat from said cabinet, refrigerant compressing and cooling apparatus outside of said cabinet, a capillary flow-restricting tube providing substantially the sole flow-impeding device for the relatively warm liquid refrigerant flowing from said refrigerant-cooling apparatus to said evaporator, and a suction tube for conducting the relatively cold vaporized refrigerant 30 from the evaporator to the refrigerant-compressing apparatus, said capillary and suction tubes being in intimate metallic heat conducting relationship with one another for a substantial portion of their respective lengths, so that the relatively cold suction gas is heated and the 35 relatively warm refrigerant liquid is cooled before it enters the evaporator.
16. In refrigerating apparatus, the combination 40 of a heat insulated cabinet, a refrigerant evaporator for abstracting heat from said cabinet, refrigerant compressing and cooling apparatus outside of said cabinet, a capillary tube for conducting the relatively warm refrigerant from said apparatus to the refrigerant evaporator and providing substantially the sole flow retardation on said refrigerant between said apparatus and said evaporator, a suction conduit for conveying the vaporized refrigerant from said evaporator to said apparatus, a substantial portion of said capillary tube being bonded in intimate metallic 45 heat exchange relationship with a portion of said suction conduit to raise the temperature of said portion of said suction tube above the dew-point temperature of the ambient atmosphere of said portion of the suction conduit, and a second portion of said capillary tube between said bonded portion and said evaporator, said second portion being substantially out of heat exchange relationship with said suction conduit.
17. In refrigerating apparatus, the combination 50 of a cabinet embodying a storage compartment and a machinery compartment, an evaporator associated with the storage compartment for abstracting heat therefrom, a compressor and an air-cooled condenser disposed in the machinery compartment, a capillary tube for conveying liquefied refrigerant from said condenser to said evaporator and a suction conduit for conveying vaporized refrigerant from said evaporator to said compressor, both said 55 suction conduit and said capillary tube being bonded by a high heat transmitting material into intimate heat exchange relationship with each other for a substantial distance.
18. In refrigeration apparatus, the combination 60 of a heat insulated cabinet, an evaporator for abstracting heat from said cabinet, refrigerant-supplying apparatus outside of said cabinet, a capillary flow-restricting tube for regulating the flow of warm liquid refrigerant from the refrigerant-supplying apparatus to said evaporator, and a suction tube for conducting the relatively cold vaporized refrigerant from the evaporator to the refrigerant-supplying apparatus, said suction tube being in intimate heat conducting relationship with said capillary tube, 65 and a substantial portion of the both suction and capillary tubes in said intimate heat conducting relationship being convoluted.

GRAHAM S. McCLOY.
